(57) **CLAIM**

The ornamental design for a writing instrument, as shown and described.

DESCRIPTION

FIG. 1 is a perspective view as seen from the top, front and right side of a first embodiment of a writing instrument showing our new design;

FIG. 2 is a top plan view thereof;
FIG. 3 is a left side elevational view thereof, the right side elevation being a mirror image thereof;
FIG. 4 is a bottom plan view thereof;
FIG. 5 is a front elevational view thereof;
FIG. 6 is a rear elevational view thereof;
FIG. 7 is a perspective view as seen from the top, front and right side of a second embodiment of a writing instrument showing our new design;
FIG. 8 is a top plan view thereof;
FIG. 9 is a left side elevational view thereof, the right side elevation being a mirror image thereof;
FIG. 10 is a bottom plan view thereof;
FIG. 11 is a front elevational view thereof;
FIG. 12 is a rear elevational view thereof;
FIG. 13 is a perspective view as seen from the top, front and right side of a third embodiment of a writing instrument showing our new design;
FIG. 14 is a top plan view thereof;
FIG. 15 is a left side elevational view thereof, the right side elevation being a mirror image thereof;
FIG. 16 is a bottom plan view thereof;
FIG. 17 is a front elevational view thereof;
FIG. 18 is a rear elevational view thereof;
FIG. 19 is a perspective view as seen from the top, front and right side of a fourth embodiment of a writing instrument showing our new design;
FIG. 20 is a top plan view thereof;
FIG. 21 is a left side elevational view thereof, the right side elevation being a mirror image thereof;
FIG. 22 is a bottom plan view thereof;
FIG. 23 is a front elevational view thereof;
FIG. 24 is a rear elevational view thereof;
FIG. 25 is a perspective view as seen from the top, front and right side of the writing instrument of FIG. 13 or 19 with a cap over the writing end of the writing instrument showing our new design;
FIG. 26 is a top plan view thereof;
FIG. 27 is a left side elevational view thereof, the right side elevation being a mirror image thereof;
FIG. 28 is a bottom plan view thereof;
FIG. 29 is a front elevational view thereof; and,
FIG. 30 is a rear elevational view thereof.
